UNITED STATES PATENT OFFICE.

GEORGE F. GIESECKE, OF LEIPSIC, SAXONY, GERMANY.

DESIGN FOR A TYPE-BORDER.

SPECIFICATION forming part of Design No. 16,842, dated August 10, 1886.

Application filed November 18, 1884. Serial No. 148,963. Term of patent 7 years.

To all whom it may concern:

Be it known that I, GEORGE F. GIESECKE, of Leipsic, Kingdom of Saxony, Empire of United Germany, have invented and produced 5 a new and original Design for a Font of Printing-Type, of which the following is a specification.

The figure represents a face view of my newly-designed border.

10 The leading feature of my design consists in the convoluted leaf which runs throughout the whole border, giving the general appearance of climbing or running vines in graceful tracery. Mingled with the leaves are various 15 and diverse figures, which harmonize with one another, though dissimilar, and, scattered amidst the leaves, form a pleasing whole and a united design. These figures may take manifold forms and vary without affecting the general tone of the border. Cherub and satyr

heads peep from the leaves, amid which cupids seem to float. Artists' heads in profile muse and infants' smiling countenances appear. Founts on dolphins reared and on columns supported add to the effect. Flowers from 25 which fairies spring are shown. Other forms, male and female heads, festoons, and garlands are placed and strung along the border.

Having described my design, I claim—

The design for a border herein shown and 30 described, the same consisting in a number of convoluted leaves formed in a general tracery, amid which are mingled various forms and figures, the whole having the general appearance of the border in the accompanying illustration. 35

GEORGE F. GIESECKE.

In presence of—

JOHN K. TETLOW,
FRED. P. WILKIE.
